(57) **CLAIM**

The ornamental design for a display screen or portion thereof with icon for presentation of analyte data, as shown and described.

DESCRIPTION

The file of this patent contains at least one drawing executed in color. Copies of this patent with color drawings will be provided by the Office upon request and payment of the necessary fee.

FIG. 1 shows a front view of a first embodiment of a display screen or portion thereof with icon for presentation of analyte data that incorporates the new, original, and ornamental design;

FIG. 2 shows a front view of a second embodiment of the display screen or portion thereof with icon for presentation of analyte data that incorporates the new, original, and ornamental design;

FIG. 3 shows a front view of a third embodiment of the display screen or portion thereof with icon for presentation of analyte data that incorporates the new, original, and ornamental design; and,

FIG. 4 shows a front view of a fourth embodiment of the display screen or portion thereof with icon for presentation of analyte data that incorporates the new, original, and ornamental design.

The broken lines in the drawings illustrate a display screen or portion thereof and portions of the graphical user interface and form no part of the claimed design.

**1 Claim, 4 Drawing Sheets
(2 of 4 Drawing Sheet(s) Filed in Color)**

Related U.S. Application Data

division of application No. 29/583,284, filed on Nov. 3, 2016, now Pat. No. Des. 799,542, which is a division of application No. 29/509,286, filed on Nov. 14, 2014, now Pat. No. Des. 773,529.
